CLAIM

The ornamental design for a lift table, as shown and described.

DESCRIPTION

FIG. 1 is a top, front, and left perspective view of a lift table, showing our design.

FIG. 2 is a rear, front, and left perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is an enlarged partial view of detail 9 taken from FIG. 2.

The broken lines shown in the drawings are included for the purpose of illustrating portions of the lift table that form no part of the claimed design.
